HAND TOOL FOR MAKING RUGS, CARPETS,
AND THE LIKE WITH A CUT PILEMelvin Sivyer Hurley, Tondu, near
Bridgend, EnglandApplication December 7, 1949, Serial No. 131,537
In Great Britain December 10, 1948

10 Claims. (Cl. 112—80)

1

This invention has for its object the provision of a new or improved hand tool for making rugs, carpets and the like with a cut pile.

Rug-making hand tools hitherto used have usually comprised a piercing needle to which the wool or other yarn is supplied in continuous length, the needle being tubular and having a stop member which determines the extent to which it can penetrate the hessian or other backing material. With this known kind of hand tool the needle is operated to pierce a succession or row of holes in the backing material and leave therein a length of the yarn forming a continuous or connected series or row of loops, one for each hole, the size or length of each loop being determined by the position of the limiting stop on the needle. After a row or number of rows of connected loops have been inserted in the backing material in this way, the loops require to be cut with a pair of scissors to produce a cut pile.

My improved hand tool comprises two main or body members which are in sliding engagement with each other and are provided with handles by which each can be reciprocated on the other, and the first member carries a piercing needle for inserting the loops of wool into the backing material and the second carries means for holding a completed loop and scissors for cutting the loop, the scissors being positively opened and closed by means carried by the first member and co-operating with one blade of the scissors at appropriate points in the relative movement between the members.

The two body members are conveniently formed from sheet metal and are of channel section, the flanges of one member having outwardly cranked lips which are slidably received in complementary guiding grooves on the flanges of the other member.

The scissors and the loop holding means are carried by superimposed flexible arms mounted in the channel of the second body member so that they are resiliently urged towards the needle on the other member, and the projecting part of the needle which is forced through the backing material is conveniently of channel section so that it forms a guide for the scissors, and when the scissors are advanced through the backing material they pass through the hole which the needle has made and in which it lies. Then when the needle is withdrawn the spring arm pushes the needle over and the tool is moved bodily over so that when the needle is inserted again it makes a fresh hole in the backing mate-

2

rial spaced at a predetermined distance from the preceding one, the re-insertion of the needle closing the scissors to cut the previously made loop and the withdrawal of the scissors causing them to be opened again.

One practical form of my improved tool is illustrated by way of example in the accompanying drawings in which:

- Figure 1 is a side elevation of the tool.
10 Figure 2 is a similar elevation from the other side.
Figure 3 is an end view of the tool on a larger scale.
15 Figure 4 is an elevation from the inside of one body member of the tool and the parts associated with it.
Figure 5 is a similar elevation from the inside of the other body member and the parts associated with it.
20 Figure 6 is a section on the line 6—6 of Figure 5.

Figures 7, 8 and 9 are elevations of the lower part of the tool showing the parts in three different positions in the formation and cutting of a loop of wool.

In the drawings 10, 11 are the two co-operating main or body members of the tool. Both are made from steel sheet and are of channel section with their open faces abutting. The flanges of the member 11 are formed with outwardly cranked lips 12 which are slidably received in complementary guiding grooves 13 on the member 10 formed by folding the edges of the flanges of the member 10 as shown more particularly in Figure 3.

The two members are thus coupled together for relative sliding movement in a longitudinal direction.

Each of the members 10, 11 is provided with a loop handle 14 formed from a bent strip of metal secured at its ends to the member, the grip part of the handle preferably being covered with plastic for comfort.

At the lower end of the member 10 the flanges of the channel are partially cut away and the remainder is tapered to form a pointed needle 15. An eye 16 is pierced in the needle a short distance from its point and the metal above the eye is pressed in as shown at 17 to form a lead for the wool which is threaded through the eye. The wool is guided to the eye by threading it through an opening in a lug 18 projecting from a channel shaped pressing 19 which is secured to the body member by a nut 20 on a screw 21. The lug 18 also forms a stop to limit the penetra-

tion of the needle through the backing material and hence the length of the loop made in the wool, and if it is desired that this should be adjustable a longitudinal slot may be provided in the pressing 19 for the screw so that by slackening the nut 20 the lug 18 can be adjusted longitudinally relative to the needle. The nut 20 may also serve as shown to secure the lower end of the handle.

The means for securing the upper end of the handle to the member 10 also secure the upper end of a blade spring 22, and the lower end of the spring has secured to it a channel shaped pressing 23 which freely embraces the member 10 and the limbs of which extend over the sides of the member 11. One limb of the pressing is cut away as shown in Figure 1 to form a substantially rectangular lug 24 which works between a laterally extending tongue 25 cranked outwardly from the lower end of one side of the member 11 and a projecting lug 26 on a pressing 27 secured to the member 11 at its upper end. The lug 24 working between the lugs 25 and 26 limits the relative longitudinal displacement of the members 10 and 11, and if desired the pressing 27 carrying the upper lug may be longitudinally adjustable on the member 11.

The other limb of the pressing is cut away as shown in Figure 2 to form a cam 28 of which the bottom edge is at right angles to the longitudinal axis of the tool and the upper edge is inclined.

In the inside of the channel of the member 10 there is fixed a hardened steel strip 29 of which the lower end is shaped to form a cam or tooth 30 projecting forwardly towards the other member and adapted to engage one limb of the scissors to open the scissors as described below. The strip 29 is secured to the member 10 by a screw 31 and the strip may be formed with several longitudinally spaced holes 32 as shown in Figure 4 to receive the screw so that the longitudinal position of the tooth 30 can be adjusted.

The member 11 has secured within its channel two superimposed spring steel strips 33, 34, as shown in Figures 5 and 6, which are secured to the member at their upper ends by a screw 35. Both strips are curved so that their free ends diverge from the base of the channel as shown more particularly in Figure 6, and one or each of the strips may be made longitudinally adjustable on the member 11 by providing it with a slot or with several longitudinally spaced holes for the screw 35. The free end of the inner strip 33 carries two or more parallel downwardly projecting pins 36, of which only one appears in the drawings, and which are clamped between the lower end of the strip and a sheet metal clamping member 37 which is secured to the strip by rivets 38. The clamping member 37 has an outwardly cranked lug 39 adapted to engage the backing material and to limit the penetration of the pins and the scissors.

The free end of the other strip 34 is shaped to form one blade 40 of the scissors, and the other blade 41 is pivoted to it by a rivet 42. The tail of the blade 41 is extended upwardly and is shaped to form a lug 43 which projects through a gap formed by cutting away a portion of one side wall of the member 11. The lug 43 has an inclined edge 44 for engagement with the cam 28 on the pressing 23 to close the scissors and a pointed heel part 45 for engagement by the tooth 30 on the strip 29 to open the scissors. The points of the scissors are arranged to project from the

lower end of the member 11 for substantially the same distance as the pins 36.

The two strips 33, 34 carrying the pins and the scissors can be flexed towards the base of the member 11 but the extent of this movement is limited by the engagement of the strip 33 with a screw 46 which is adjustably screwed through a nut 47 on the inside of the base and is locked by a nut 48 which lies outside the base and also serves to hold the lower end of the handle 14.

When the two body members are assembled together and are in substantial alignment in a longitudinal direction as shown in Figures 1 and 2 the resilience of the strips 33 and 34 holds the scissors blades within the channel of the piercing needle. The two body members can be separated or engaged with each other when desired by forcing the pressing 23 rearwardly on its spring blade 22 far enough to allow it to clear the lug 25 or the lug 26 and then sliding the one member longitudinally relative to the other.

The operation of the tool is shown in Figures 7, 8 and 9 in which the canvas or other backing material is shown at 49 and the wool at 50. The wool is threaded through the hole in the lug 18 and through the eye of the needle.

Holding the tool vertically by the handles the operator moves the member 10 downwardly to force the needle 15 through the backing 49 until its progress is arrested by the lug 18. The needle carries the wool with it through the backing to form a loop 51. The parts are then in the position shown in Figure 7.

The member 11 is then moved downwardly until the lug 39 engages the backing. The scissors, which are open, slide down inside the channel part of the needle through the hole made by the needle and straddle the wool loop adjacent to the eye of the needle, and the pins 36 straddle the previously formed loop, if any, and hold it against the backing. The parts are then approximately in the positions shown in Figure 8. In the downward movement of the member 11 the lug 43 on the angularly movable blade 41 of the scissors engages the inclined upper edge of the lug 28 and simply pushes the member 23 aside as shown in Figure 8 so that the scissors are not affected.

Next the member 10 is drawn upwardly again to withdraw the needle from the backing, and the needle leaves behind it the formed loop with its bight straddled by the open scissor blades as shown in Figure 8.

The whole tool is then displaced laterally, to the right in the drawings, to the extent allowed by the flexing of the spring strings 33 and 34 as limited by the screw 46.

The needle is thus displaced laterally from the first hole through a predetermined distance and when the member 10 is moved downwardly again it makes a fresh hole in the backing and takes the wool with it to make another loop. In this movement of the member 10 the inclined edge 44 of the lug 43 is engaged by the bottom edge of the cam 28 which forces the lug 43 inwardly to close the scissors and cut the loop straddled by them.

The member 11 is then drawn upwardly to withdraw the scissors from the first hole and return the parts to the position shown in Figure 7, and as the member 10 is approaching the end of this movement the tooth 30 engages the point 45 on the blade 41 of the scissors and positively opens the scissors again.

The resilience of the strips 33 and 34 moves the

scissors back into engagement with the needle and as the member 11 is moved downwardly again the scissors pass through the hole just made by the needle while the pins 36 hold down the wool in advance of the cut which has been made to ensure that the wool feeds through the needle when the needle is again withdrawn.

Positive opening and closing of the scissors allows the blades to be set in really effective engagement with each other and ensures a clean cut of each loop of the wool.

The above description of the operation of the tool is necessarily somewhat complicated as the functional relationship between the various parts during the relative movement of the two body members has had to be explained in detail but the actual practical operation of the tool is extremely simple.

After threading the wool through the needle the operator simply holds the tool vertically over the backing material and reciprocates the two members alternately in a vertical direction while maintaining a downward and lateral pressure on the tool.

Successive rows of cut loops can thus be made very quickly and with a minimum of effort.

I claim:

1. In a hand tool for making cut pile rugs having two body members carrying a loop inserting needle and loop cutting scissors respectively which members are interengaged for manually controlled longitudinal sliding movement relatively to each other to permit the scissors to be advanced through a hole which the needle has made in backing material and to straddle the loop inserted through the hole by the needle, means for positively closing and opening the blades of said scissors at appropriate points in the relative movement between the members, said means including a rigid abutment on a movable blade of the scissors, a fixed abutment on said needle carrying member adapted to enter into positive sliding engagement with said movable blade abutment to open the scissor blades when the scissor carrying member is withdrawn from the backing material, and a spring loaded abutment on the needle carrying member adapted to enter into positive sliding engagement with said movable blade abutment to close the scissor blades when the needle is inserted in the backing material.

2. A hand tool as specified in claim 1 wherein the movable blade of the scissors is pivoted to a resilient strip secured at one end to the scissor carrying member, the other end of said strip being shaped to form a fixed scissor blade co-operating with the movable blade and both blades being inclined toward said needle carrying member.

3. A hand tool as specified in claim 1 including two superimposed resilient strips secured at one end to the scissors carrying member and curved to bias their free ends towards the needle carrying member, loop holding pins on the free end of one strip immediately adjacent the scissor carrying member, and a fixed scissor blade formed on the free end of the other strip, the movable scissor blade being pivoted on and curved to conform to the curvature of said fixed scissor blade.

4. A hand tool for making cut pile rugs comprising in combination, two channel-section body members having their longitudinal edges bent outwards to form flanges extending the complete length of the members, grooves formed by the flanges of one member, said grooves adapted to receive the flanges of the other member so that

the members are slidably engaged for relative longitudinal movement, a piercing and wool-receiving needle projecting from an end of one of the members for inserting loops of wool into backing material, scissors for cutting the loops yieldingly mounted in and projecting from the adjacent end of the other member, said scissors being curved to incline towards the needle to permit the scissors to be advanced through a hole which the needle has made in the backing material and to straddle the loop inserted in the hole by the needle, a rigid abutment projecting from one blade of the scissors, a spring-loaded saddle shaped abutment mounted on and straddling the needle body member, said saddle-shaped abutment being adapted to enter into positive sliding engagement with said scissor abutment to close the scissors when the needle is inserted in the backing material, a fixed abutment secured within the channel of the needle body member and adapted to enter into positive sliding engagement with said scissor blade abutment to open the scissors when the scissors body member is withdrawn from the backing material, and stops on the scissors body member adapted to engage with said saddle shaped abutment to limit longitudinal movement of the body members relatively to each other.

5. A hand tool as specified in claim 4 having means for holding a completed loop yieldingly mounted in and projecting from the scissors body member, said loop holding means being interposed between the scissors and the scissors body member and curved to incline towards the needle.

6. A hand tool as specified in claim 4 wherein one of the stops is adjustable.

7. A hand tool as specified in claim 4 having means for holding a completed loop yieldingly mounted in the scissors body member and projecting with the scissors therefrom, a stop on said loop holding means limiting insertion of the loop holding means and scissors in the backing material, and an apertured stop on the needle body member limiting insertion of the needle in the backing material.

8. A hand tool for making cut pile rugs from a continuous length of yarn comprising in combination, body members interengaged for restricted manually controlled longitudinal sliding movement relatively to each other, a fabric piercing needle on one body member, scissors on the other body member to cut a loop of yarn carried through a hole pierced in the fabric by said needle, means whereby the pivoted blades of the scissors are normally maintained in an open position, a tail movable with a movable blade of the scissors but in opposite direction to said movable blade, and an abutment on the needle body member adapted to enter the path of said tail as the scissors are withdrawn from the fabric to displace the tail so that the scissors are closed whereupon the scissors are immediately reopened by the aforesaid means.

9. A hand tool for making cut pile rugs from a continuous length of yarn comprising, in combination, two body members interengaged for manually controlled longitudinal sliding movement relatively to each other, a fabric piercing needle on one body member, scissors on the other body member to cut a loop of yarn carried through a hole pierced in the fabric by said needle, said scissors including a fixed blade and a movable blade pivoted on the fixed blade, resilient means integral with the fixed scissor blade and normally urging the scissors towards

the needle, a tail on the movable scissor blade, opposed cam surfaces on said tail, a first abutment on the needle body member adapted to engage one of said cam surfaces to close the scissor blades during withdrawal of the scissors from the fabric, and a second abutment on the needle body member adapted to engage the other cam surface to open the scissor blades immediately after they have been closed by said first abutment.

10. A hand tool as specified in claim 9 wherein relative movement of the body members is restricted by a stop on the needle body member engaging one or the other of spaced stops on the scissors body member, said stop on the needle body member being resiliently urged into the 15 path of the spaced stops and adapted to be dis-

placed from this path to permit unrestricted relative movement of the body members.
